UNITED STATES PATENT OFFICE.

GEORGE MARIE CAPELL, OF PASSENHAM, COUNTY OF NORTHAMPTON,
ENGLAND.

ROTARY FAN.

SPECIFICATION forming part of Letters Patent No. 324,006, dated August 11, 1885.

Application filed June 9, 1884. (No model.) Patented in England June 22, 1883, No. 3,117.

To all whom it may concern:

Be it known that I, GEORGE MARIE CAPELL, a subject of the Queen of Great Britain, residing at Passenham, in the county of Northampton, England, have invented certain new and useful Improvements in Rotary Fans, of which the following is a specification.

Figures 1 and 2 are respectively back and front perspective views of an induction-fan made according to this invention, with the outer case removed for the sake of showing the construction of the body of the fan.

A is the central collecting-cylinder, and BB its ports. Each port carries a curved blade, C, dipping from the cylinder A toward its axis. It is advantageous that the radius of these blades should be the same, or nearly so, as that of the cylinder A. The blades are sometimes continued to the boss of the fan for the purpose of securing additional strength when a blast of high pressure or velocity is required.

D is a disk having ports FF formed in it, and carrying blades E E. The lines at which these blades spring from the disk D, as well as the lines forming the sides of the ports FF, are always radial to the common center. The radius of the blades, buckets, or collectors H H is also the same as that of the cylinder A.

G is a scalloped peripheral band forming with the blades E E displacers or collectors H H, which by creating vacuums behind them induce currents of air through the ports F F. The inner edges, e e, of the blades E E may be continued till they meet the cylinder A.

Fig. 3 is a front elevation, and Fig. 4 a side elevation, partly in section, showing a method of mounting this improved fan as a ventilating-fan in the wall of a building or to the face of a mine-drift, or for any other purpose. Fig. 5 is a side elevation of an improved blast-fan made according to this invention, but with the buckets or collectors on the opposite side of the disk D.

The currents of air from the ports in the disk D and the cylinder A are thus discharged on the same side of the disk as the collecting-cylinder A. This cylinder has one end, I, closed, and a boss, J, thereon. It may also have, in the case of large and consequently heavy fans,

a second boss and arms springing therefrom to join the disk. These arms are at an angle with the vertical plane, with their front edges leading, insomuch that they will assist, as they revolve, in driving the air toward the interior of the cylinder and in the direction of the air-currents.

Although the ports of the cylinder A are shown closely contiguous to those of the disk D, they may, according to this invention, be separated therefrom by any required distance when such a construction may be desirable, provided that both cylinder and disk are rotated on a common shaft.

The most suitable number of ports and blades for one fan is six of each in the cylinder A and eight in the disk D; but these numbers may be varied as may be necessary.

Fig. 6 shows another form of port with a segmental hood instead of blade E and band G, as illustrated in Figs. 1, 2, 3, and 4. This hood K is the equivalent of the bucket or collector H, described above. Both hood and port are struck with the same radius as the central cylinder of the fan. The rear edge, h, of this segmental hood meets a diameter where the latter cuts the circumference of the disk D, (as indicated by the dotted line,) the port F being moved slightly behind the inner edge of the hood.

What is claimed is—

1. In an exhaust or blast fan or fan-wheel, the combination of a collecting-cylinder, A, closed at one end, and provided with port-holes B and blades C, joining the edge of one side of the ports and dipping toward the axis, the curve of said blades corresponding (or nearly so) with the radius of the cylinder in which the ports are formed, a disk, D, provided with ports F, blades E, and scalloped peripheral band G, for collecting or inducing currents of air, as herein set forth and illustrated.

2. In an exhaust or blast fan or fan-wheel, the combination of a disk, D, provided with ports F, blades E, and scalloped peripheral band G, for collecting or inducing currents of air, with a central collecting-cylinder, A, provided with ports B and blades C, all as herein set forth and illustrated.

3. In exhaust or blast fans or fan-wheels of

the herein described construction, the combination, with the collecting-cylinder A, of a disk, D, provided with ports F and wings E on the same side as the collecting-cylinder A, for inducing currents of air, as herein set forth and illustrated.

5 In testimony whereof I hereunto sign my

name, in the presence of two subscribing witnesses, this 18th day of January, 1884.

GEORGE MARIE CAPELL.

Witnesses:

G. W. WESTLEY,

JNO. DEANE,

Both of 17 Gracechurch Street, London.
